Attorney.

UNITED STATES PATENT OFFICE.

WENDELIN P. SENG, OF CHICAGO, ILLINOIS.

FLAG-HOLDER ATTACHMENT FOR AUTOMOBILES.

1,240,377.

Specification of Letters Patent. Patented Sept. 18, 1917.

Application filed July 8, 1916. Serial No. 108,237.

To all whom it may concern:

Be it known that I, WENDELIN P. SENG, a citizen of the United States, residing at Chicago, county of Cook, and State of Illinois, have invented a new and useful Flag-Holder Attachment for Automobiles, of which the following is a specification.

This invention relates to an attachment especially designed for use upon automobiles and other vehicles and intended as a convenient means for securely holding the standards of flags, banners, etc., generally employed during festive occasions for decorative purposes.

15. The objects and advantages of the invention, together with the novel features thereof, will be hereinafter described and more particularly pointed out in the appended claims.

20. Referring to the drawing:

Figure 1 is a perspective view of a flag-holder typifying an embodiment of my invention;

Fig. 2 is a front elevation of the same; 25 and

Fig. 3 is a vertical, central, transverse section of the holder, a flag-pole or standard being shown in position therein.

I construct the hereinafter described flag-holder attachment from a blank of spring-wire of suitable gage and length. The blank is bent at its middle upon itself, as at 1, thus forming opposite nearly parallel terminals 2, which at points at one side of their middles, are rebent upon themselves, as at 3, to form opposite companion upwardly disposed substantially parallel terminals 4, which at points approximately transversely opposite the bend 1, are rearwardly disposed 35 and converged to form a horizontal shank 5. This shank may be of any desired length, and beyond the same each terminal is bent in approximately semicircular form to form 40 one member of a spring-jaw 6, the ends of the jaws, when not spread, meeting at the point 7.

It will be seen that by reason of the described bending of the blank there is produced upper and lower spring-jaws 8 and 9 respectively. The outer jaw 8 is preferably flared, as shown, as is also the two lower jaws 9.

The spring-jaw members 6, it will be understood, are by reason of their relative 55 adjustability, adapted to clamp about a convenient cylindrical object, generally one of

the bolts of the lamp-brackets of an automobile, and to be held thereon by the nuts of such bolts.

An ordinary flag-pole or staff 10 may be 60 readily inserted downwardly between the jaws 8 and 9 of the holder, and when so positioned, it will not only be embraced at opposite sides by said jaws, but also at four different points by the terminals 2 and 4. 65 It will be apparent that in this manner the staff will be held securely in position, and may be readily inserted or removed when desired. The device being formed of spring-wire will readily and automatically adjust 70 itself to staffs of various diameters.

Having described my invention, what I claim is:

1. The herein described flag-holder attachment, the same formed of a blank of 75 spring-wire bent at its middle and at each side thereof to form upper and lower pairs of outwardly flaring spring-jaws, the jaws of each pair being spaced apart and those of one pair being angularly disposed with 80 relation to those of the remaining pair, the terminals of the blank beyond the jaws being bent to form a right-angularly disposed shank terminating in opposite curved bolt embracing members, the spacing of the jaws 85 of each set of jaws being such that they are adapted to pass and clamp a staff of suitable size.

2. The herein described flag-holder attachment, the same consisting of a spring-wire blank bent at its middle to form one member of an upper jaw and opposite depending terminals, the latter being rebent at one side of their middles to form a pair of lower spaced apart jaws at angles to the 90 upper jaw-member and ascending terminals, and at points substantially opposite the middle bend of the blank, disposed at right angles to the ascending terminals and combined to form the second member of the 95 upper jaw and a shank, the ends of the latter being bent in semicircular form to produce opposite bolt embracing members, the spacing of the jaws of each set of jaws being such that they are adapted to pass 100 and clamp a staff of suitable size.

3. The herein described flag-holder attachment, the same consisting of a spring-wire blank bent at its middle to form one member of an upper jaw and opposite depending terminals, the latter being rebent at one side of their middles to form a pair 110

of lower spaced apart jaws at angles to the upper jaw-member and ascending terminals, and at points substantially opposite the middle bend of the blank, disposed at right angles to the ascending terminals and combined to form the second member of the upper jaw and a shank, and beyond the latter bent to produce an attaching means, the spacing of the jaws of each set of jaws being such that they are adapted to pass and clamp a staff of suitable size.

4. The hereinafter described flag-holder attachment, the same consisting of a spring-wire blank bent at its middle to form one member of an upper jaw and depending terminals, the latter being outwardly disposed and bent upon themselves to form one member of the upper flared jaw and at

their lower ends recurved upon themselves to form opposite lower jaws at angles to the upper jaw-member and divergently disposed, with relation to each other and ascending terminals, the latter opposite the upper jaw being laterally disposed to form a second jaw-member and a shank, and attaching-means, the spacing of the jaws of each set of jaws being such that they are adapted to pass and clamp a staff of suitable size, at the end of the shank.

In testimony whereof I have signed my name to this specification in the presence of two subscribing witnesses.

WENDELIN P. SENG.

In the presence of—

GEO. F. HASSEL,

W. H. POTTER.
